UNITED STATES PATENT OFFICE.

SYDNEY L. PRESCOTT, OF BROOKLYN, NEW YORK.

CARBURETION SYSTEM.

1,208,207.

Specification of Letters Patent. Patented Dec. 12, 1916.

Application filed February 4, 1915. Serial No. 6,025.

To all whom it may concern:

Be it known that I, SYDNEY L. PRESCOTT, a citizen of the United States, residing at Brooklyn, county of Kings, and State of New York, have invented a new and useful Improvement in Carburetion Systems, of which the following is a specification.

This invention relates to an improvement in carburetion systems, particularly to those adapted for use in connection with power plants of automobiles, motor boats, etc.

In carburetion systems heretofore known the suction established by an engine is relied upon to effect the carburetion of air drawn into the engine during a suction stroke. During the suction stroke, the suction varies because of the variation of piston speed during the stroke. Since this suction varies, the velocity of the air also varies and the efficiency of the carbureting mechanism varies in accordance therewith. This is true whether the engine be of the single cylinder or of the multi-cylinder type. In all cases the carburetion is effected by a pulsating current of air, each pulsation being variable.

One of the objects of the present invention is the production of a carburetion system comprising a carbureter including operative connections and a source of fuel supply, and means for maintaining a current of air at substantially constant velocity at the source of fuel supply during the suction stroke of an engine in connection with which the device is used so that carburetion will depend, not upon the variable pulsations heretofore relied upon, but upon a current of air flowing at substantially constant velocity throughout the suction stroke of the engine.

In carburetion systems heretofore used, it has frequently been found difficult to insure a full charge of explosive gas in the cylinder or cylinders of an engine because the suction established by the engine is relied upon for supplying the charge of gas, and any leak in the intake manifold or piston fittings, or stream resisting obstructions due to faulty design or construction, interfere with the flow of gas from the carbureting device to the engine cylinders, and in consequence an

uncertain supply of gas reaches the cylinders.

It is another object of the invention to produce a carburetion system in which a definite quantity of gas is delivered to the cylinders of the invention during the normal operation of the same, this quantity substantially equaling in volume the normal capacity of the cylinders, although it may be varied if desired.

Another object of the invention is the production of a carburetion system in which a current or blast producing mechanism is employed, this mechanism being adapted to deliver a definite quantity of air to the engine cylinders and being itself adapted to be controlled by the engine in connection with which it is used, so that the blast will vary in volume in accordance with variations of engine speed. Means for carbureting the air are also used in connection therewith.

Another object of the invention is the production of a carburetion system in which an air blast mechanism is used, this mechanism receiving the air from air heating means and forcing the heated air through a carbureter to the cylinders of an engine.

Another object of the invention is the production of a carburetion system unitary in construction; that is to say, having an air current or blast producing means inbuilt with the carbureting means.

With these and other objects not specifically mentioned in view, the invention consists in certain parts, constructions and combinations which will be hereinafter fully described and then specifically pointed out in the claims hereunto appended.

In the accompanying drawings, which form a part of this specification and in which like characters of reference indicate the same or like parts, Figure 1 is a plan view, partly in section, of a device constructed in accordance with the invention; Fig. 2 is a side elevation of the device illustrated in Fig. 1, this figure being also shown partly in section; and Fig. 3 is a diagrammatic view indicating the application of the device to an engine.

In carrying the invention into effect, there is provided means for maintaining a current

of air at substantially constant velocity at a source of fuel supply during the suction stroke of an engine in connection with which the device is used. While this current maintaining means may, in some constructions, consist of a current inducing device; in the best constructions, it will consist of a device for forcing a current of air, or in other words—producing a blast of air. There is further provided, in the best constructions, operating means for the current maintaining means, this operating means being controlled by the engine in connection with which the device is used, so that the current or blast of air will vary in accordance with variations of engine speed. In the best constructions also, the capacity of the blast producing means, or other current maintaining means, will be substantially equal to the normal capacity of the engine cylinders, so that the device will be efficiently operative irrespective of the condition of the intake mechanism, piston fittings and other elements heretofore relied upon for filling the cylinders with gas. In the best constructions also, there is provided means for maintaining and delivering a blast of air to the cylinders of an engine during the normal operation of the same and means for carbureting the air, the carbureting means being located between the blast maintaining means and the engine. In the best constructions also, a float carbureter will be used in the system, and means for heating the air will also be provided. In those constructions where a blast maintaining means and carbureting means are used, said means may be inbuilt to form a unit. All of the above elements may be varied in construction within wide limits.

The device selected to illustrate the invention is but one of many possible concrete embodiments of the same, and the invention therefore is not to be restricted to the precise details of the structure shown and described. Moreover, certain parts of the invention are capable of use independent of other parts, and such independent use is contemplated.

In the device selected to illustrate the invention, a blast producing device is employed which includes a fan 1 of the "sirocco" type, mounted upon a shaft 2, which shaft carries a pulley 3. While in certain constructions this fan may be driven from any suitable source of power, yet it is adapted to be driven or controlled by an engine in connection with which the device is used, so that the speed of the fan—and consequently its capacity—will vary in accordance with variations of the engine speed. A belt 4 is provided for this purpose which runs over the pulley 3 and also over any suitable rotating part of the engine (not shown), or of any other suitable source of

motion. The fan 1 is inclosed in a casting 5. The rear of this casting is closed by a plate 6 which carries a boss 7 in which the shaft 2 is journaled. The front of the casting is partially closed by a plate 8 having an air intake 9 formed thereon. The two plates 6 and 8 are held in position by a series of through bolts 10 extending through the casting 5 and the plates 6 and 8.

The fan is adapted to draw air in through the intake 9 and deliver it tangentially in a steady current or blast, and the delivered blast may be conducted to any desired point, and means for carbureting the air may be located on either side of the blast maintaining means. In the device selected to illustrate the invention, however, the blast maintaining means is inbuilt with the carbureting means and although other carbureters may be combined with a blast maintaining means, whether or not the two mechanisms are inbuilt, the carbureter shown as inbuilt with the blast maintaining means forms the subject matter of my co-pending application, Serial No. 874972, filed December 1, 1914, and reference is made to said application for a full disclosure of the purposes, mode of operation and construction of such carbureter. For present purposes, it is sufficient to note that the carbureter includes movable intake amplifiers 12 and 13 which form an intake of variable capacity; a fuel nozzle 52 located between the amplifiers; and an air nozzle 67 located within the fuel nozzle. The carbureter further includes a throttle shaft 44, a throttle lever 50, stop arms 46, and adjusting screws 47. For the purpose of providing easy access to the fuel nozzle 52 and air nozzle 67, the casting 5 is provided with an opening which is normally closed by a plug 11 held in position by one or more screws 14.

By an inspection of Fig. 2, it will be readily understood that the blast produced by the fan 1 is delivered directly through the intake of the carbureter between the amplifiers 12 and 13. It will also be readily understood that a portion of the blast goes directly through the air nozzle 67, and that fuel issuing from the fuel nozzle will be in the form of an exceedingly thin tubular stream having air in contact with its interior as well as with its exterior, so that the greatest possible surface of fuel will be directly exposed to air flowing at constant velocity whenever the engine is running at constant speed.

It may be here remarked that for different sized engines different sizes of blast maintaining means will be desirable, and it is to be understood that in carrying the invention into practice the size of the blast maintaining means, as well as the size of the carbureter, will depend upon the size of the

engine in connection with which they are to be used. In so far as varying speeds of the engine is concerned, no change is necessary either in the carburetor or in the blast maintaining means, for both have sufficient capacity, especially when the blast maintaining means is driven directly by the engine to meet the requirements throughout the range of engine speeds, and this is done automatically.

From the carburetor, the gas is delivered to an intake manifold 15, which conducts it to the cylinders of an engine shown diagrammatically in Fig. 3 and marked 16.

15. For the purpose of heating the air to insure high efficiency, there is provided a pipe 17, one end of which slips into the intake 9 before referred to, and the other end of which is in open communication with a 20 heater 18 of well known construction, surrounding an exhaust pipe 19, which exhaust pipe is connected with an exhaust manifold 20 in communication with the engine cylinders.

25. It will be readily understood that the fan 1 draws the heated air through the heater 18 and pipe 17 into its own interior, and then forces the heated air through the carburetor to the cylinders of an engine. During that 30 portion of the suction stroke of an engine in which the suction is low due to the low speed of the piston, the blower or blast maintaining means maintains the necessary velocity at the source of fuel supply or at the delivery end of the fuel nozzle, the gas ahead of it being slightly compressed in the intake manifold. At that portion of the piston travel, during the suction stroke, at which it travels at its highest speed, this slight pressure is relieved. Since the capacity of the 40 blast maintaining means is substantially equal to the normal capacity of the engine cylinders, and since the velocity of the air past the fuel nozzle is substantially constant irrespective of the speed of the piston or 45 pistons during the suction stroke, the effective result is the production of a more uniform gas than has heretofore been possible, and also the delivery to the cylinders of the 50 engine of a full charge of gas irrespective of defects due to faulty design, or to wear, or to weather conditions.

As above pointed out, the air may be carbured before it passes through the blast 55 maintaining means; and in such case, the blast maintaining means would operate upon gas and not upon air. Any suitable means may be employed for carbureting the air, irrespective of its location. Any suitable 60 means may be employed for heating the air before it is carbured or for heating the resultant gas after it is carbured.

What is claimed is:

1. In a carburetion system, the combina-

tion with an air intake having co-acting 65 rocking members provided with coöperating circumferential progressively expanding grooves semi-circular in cross section, said members being operative by a current of air established therebetween and acting thereupon to vary the amplitude of the passage between said members in accordance with variations in the air current, of a manifold connected and coöperative with said air intake, and means for producing and delivering 70 a blast of air to the intake substantially equal in volume to the normal capacity of the engine cylinders in connection with which the device is used and in such manner as to cause the air blast to coöperate with the engine suction in operating and controlling the operation of said rocking members.

2. In a carburetion system, the combination with an air intake having co-acting 75 rocking members provided with coöperating circumferential progressively expanding grooves semi-circular in cross section said members being operative by a current of air established therebetween and acting thereupon to vary the amplitude of the passage between said members in accordance with variations in the air current, of a manifold connected and coöperative with said air intake, and a blower and operative connections 80 for producing and delivering a blast of air to the intake substantially equal in volume to the normal capacity of the engine cylinders in connection with which the device is used and in such manner as to cause the air 85 blast to coöperate with the engine suction in operating and controlling the operation of said rocking members.

3. In a carburetion system, the combination with an air intake having co-acting 90 rocking members provided with coöperating circumferential progressively expanding grooves semi-circular in cross section said members being operative by a current of air established therebetween and acting thereupon to vary the amplitude of the passage between said members in accordance with variations in the air current, of a manifold connected and coöperative with said air intake, and means for producing and delivering 95 a blast of air to the intake in such manner as to cause the air blast to coöperate with the engine suction in operating and controlling the operation of said rocking members.

4. In a carburetion system, the combination with an air intake having co-acting 100 rocking members provided with coöperating circumferential progressively expanding 105 grooves semi-circular in cross section said members being operative by a current of air established therebetween and acting thereupon to vary the amplitude of the passage between said members in accordance with variations in the air current, of a manifold connected and coöperative with said air intake, and means for producing and delivering 110 a blast of air to the intake in such manner as to cause the air blast to coöperate with the engine suction in operating and controlling the operation of said rocking members, said means being adapted to be 115 controlled by the engine in connection with which the device is used whereby the blast varies in volume in accordance with variations of engine speed.

4. In a carburetion system, the combination with an air intake having co-acting 120 rocking members provided with coöperating circumferential progressively expanding 125 grooves semi-circular in cross section said members being operative by a current of air established therebetween and acting thereupon to vary the amplitude of the passage between said members in accordance with variations in the air current, of a manifold connected and coöperative with said air intake, and means for producing and delivering a blast of air to the intake in such manner as to cause the air blast to coöperate with the engine suction in operating and controlling the operation of said rocking members.

- grooves semi-circular in cross section said members being operative by a current of air established therebetween and acting thereupon to vary the amplitude of the passage between said members in accordance with variations in the air current, of a manifold connected and coöperative with said air intake, and a blower and operative connections for producing and delivering a blast of air to the intake substantially equal in volume to the normal capacity of the engine cylinders in connection with which the device is used and in such manner as to cause the blast of air to coöperate with the engine suction in operating and controlling the operation of said rocking members, said blower being adapted to be controlled by the engine in connection with which the device is used whereby the blast is varied in volume in accordance with variations of engine speed.
5. In a carbureter, the combination with an air intake having co-acting rocking members provided with coöperating circumferential progressively expanding grooves semi-circular in cross section said members being operative by suction established therebetween and acting thereupon to vary the amplitude of the passage between the members in accordance with suction variations, of a fuel nozzle located between said members and concentric with the grooves thereof, an air nozzle within said fuel nozzle, and means for producing and delivering a blast of air to the intake and through the air nozzle substantially equal in volume to the normal capacity of the engine cylinders in connection with which the device is used.
6. In a carbureter, the combination with an air intake having coöperating rocking members provided with coöperating circumferential progressively expanding grooves semi-circular in cross section said members being operative by suction established therebetween and acting thereupon to vary the amplitude of the passage between the members in accordance with suction variations, of a fuel nozzle located between said members and concentric with the grooves thereof, an air nozzle within said fuel nozzle, and a blower and operative connections for producing and delivering a blast of air to the intake and through the air nozzle substantially equal in volume to the normal capacity of the engine cylinders in connection with which the device is used.
7. In a carbureter, the combination with an air intake having co-acting rocking members provided with coöperating circumferential progressively expanding grooves semi-circular in cross section said members being operative by suction established therebetween and acting thereupon to vary the amplitude of the passage between the members in accordance with suction variations, of a fuel nozzle located between said members and concentric with the grooves thereof, an air nozzle within said fuel nozzle, and means for producing and delivering a blast of air to the intake and through the air nozzle said means being adapted to be controlled by an engine in connection with which the device is used whereby the volume of air delivered varies in accordance with variations of engine speed.
8. In a carbureter, the combination with an air intake having co-acting rocking members provided with coöperating circumferential progressively expanding grooves semi-circular in cross section said members being operative by suction established therebetween and acting thereupon to vary the amplitude of the passage between the members in accordance with suction variations, of a fuel nozzle located between said members and concentric with the grooves thereof, an air nozzle within said fuel nozzle, and a blower and connections for producing and delivering a blast of air to the intake and through the air nozzle said blower and connections being adapted to be controlled by an engine in connection with which the device is used whereby the volume of air delivered varies in accordance with variations of engine speed.
9. In a carbureter, the combination with an air intake having co-acting rocking members provided with coöperating circumferential progressively expanding grooves semi-circular in cross section said members being operative by suction established therebetween and acting thereupon to vary the amplitude of the passage between the members in accordance with suction variations, of means for producing and delivering a blast of air to the intake substantially equal in volume to the normal capacity of the engine cylinders in connection with which the device is used, and means for pre-heating the air.
10. In a carburetion system, the combination with an air intake provided with movable means operative by a current of air established in the intake and acting upon said means to vary the amplitude of the intake in accordance with air current variations, of a manifold connected and coöperative with said air intake, and means for producing and delivering a blast of air to the intake to cause the manifold to act as an accumulator and the air blast to compensate for fluctuation in the engine suction and control the movement of said movable means.
11. In a carburetion system, the combination with an air intake provided with a pair of co-acting movable members operative by a current of air established in the intake and acting upon said members to vary the

amplitude of the air intake in accordance with air current variations, of a manifold connected and coöperative with said air intake, and means for producing and delivering a blast of air to the intake substantially equal in volume to the normal capacity of the engine cylinders in connection with which the device is used to cause the manifold to act as an accumulator and the air blast to coöperate with the fluctuating en-

gine suction in maintaining a constant force acting upon and for controlling the movement of said movable members.

In testimony whereof, I have signed my name to this specification in the presence of 15 two subscribing witnesses.

SYDNEY I. PRESCOTT.
